TYPE BAR ACTION FOR TYPEWRITING MACHINES

Claude T. Rice, Brooklyn, N. Y.

Application July 27, 1946, Serial No. 636,620

17 Claims. (Cl. 197—30)

1

This invention relates to writing machine or typewriter actions in general, and more especially to silent or noiseless typewriter actions.

Among the objects of the present invention, it is aimed to provide an improved silent typewriter action including an actuating key, a type bar and a connecting mechanism which effect a variable motion including an accelerated initial motion, a decelerated second motion after the type head of the type bar selected has been brought into printing position, and then a third motion resulting from the momentum generated by the initial motion characterized by a pressure blow as distinguished from a striking blow.

More specifically, the present invention aims to provide an improved typewriter action using a toggle linkage to generate an initial accelerated motion, a second decelerated motion when the toggle linkage approaches dead center, and a third motion characterized by a pressure blow as distinguished from a striking blow when the toggle linkage moves to and beyond dead center.

It is still another object of the present invention to provide an improved typewriter action using a toggle linkage cooperating with a control for connecting the toggle linkage to the type bar to generate an initial accelerated motion, a second decelerated motion when the toggle linkage approaches dead center, and a third motion characterized by a pressure blow as distinguished from a striking blow when the toggle linkage moves to and beyond dead center.

These and other features, capabilities and advantages of the present invention will appear from the subjoined detail description of specific embodiments thereof illustrated in the accompanying drawings, in which

Figs. 1 and 2 illustrate successive positions in side elevation of one embodiment.

Figs. 3 and 4 illustrate successive positions in side elevation of a second embodiment.

Figs. 5 and 6 illustrate successive positions in side elevation of a third embodiment; and

Figs. 7 and 8 illustrate successive positions in side elevation of a fourth embodiment.

In the embodiment illustrated in Figs. 1 and 2, the platen 1 is illustrative of the class of platens in which the platen is shifted to receive the upper case characters, being illustrated in its descended, normal position, to receive lower case characters. The type bar 2 is pivotally mounted on the fixed pivot pin or shaft 3, being provided with a type head having a lower case character 4 and an upper case character 5. The key bar 6, illustrative of the conventional key bar, is pivotally mounted at one end on the fixed pivot pin or shaft 7, and at its other end provided with a conventional key 8.

In the interest of an understanding of the operation of this embodiment and of showing its rela-

2

tion to the three other embodiments hereinafter to be described, it is here noted that in all four embodiments there are only three fixed pivot pins, such as the pivot pins 3 and 7 aforesaid, and the pivot pin 9 now to be described. The pivot pin 9 extends through the angle or bend in the bell crank lever or bent lever 10, which has a short broad arm 11 and a long arm 12. The arm 11 has pivotally connected thereto the upper end 10 of the link 13 which is pivotally connected at its lower end to the key bar 6. Above the pivotal connection with the link 13, the arm 11 is connected to the tension spring 14 for returning the typewriter action to normal position or position of rest after actuation thereof in accordance with convention.

The long arm 12 forms a toggle linkage with the link 15, the action of which constitutes an important, if not the main, feature of the present invention. The link 15 is pivotally connected at one end to the free end of the arm 12, and at its other end is pivotally connected to the short link 16 constituting a part of the control for the type bar 2. The link 15 is fulcrumed or pivoted intermediate its ends to the upper end of the link 17 constituting another part of the control for the type bar 2, the lower end of which link 17 is pivotally connected to the free end of the short arm or extension 18 integral with the type bar 2.

The link 15 functionally is divided into two arms 19 and 20, the arm 19 cooperating with the arm 12 to form a toggle linkage, the movement of which from the full line position shown in Fig. 1 toward the dotted line position shown in Fig. 1, upon actuation effecting an accelerated, rapid initial motion, the movement of which when approaching and passing the dead center, dotted line position shown in Fig. 1, being decelerated, and the motion of which from the dotted line position of Fig. 1 to the full line position shown in Fig. 2, being characterized by a pressure blow as distinguished from a striking blow to effect a silent or noiseless printing impression by the type bar 2.

To aid in effecting a uniform pressure blow by a plurality of actions, and in properly positioning the type bar 2 preparatory to an actuation, preferably there is provided a stop 21 which, in the present instance, is positioned to engage the rear face of the type head of the type bar 2, as shown in the full line position in Fig. 1.

Furthermore, to limit the arm 12 in the final printing position of the type bar 2 and thereby prevent any repeat printing action by the type bar 2, preferably a second stop 22 is provided, in the present instance positioned to engage the upper edge of the arm 12 in the printing position of the type bar 2.

The embodiment shown in Figs. 3 and 4 differs primarily from the embodiment shown in

Figs. 1 and 2 in that the link 16 is omitted, and in place thereof, the type bar 23 is provided with a cam slot 24 having an upper lobe 25 and a lower lobe 26. The type bar 23, in the present instance, is also shown as slightly curved as compared to the type bar 2, the arm 27 forming a sharper angle with the main part of the type bar 23, than is the angle formed between the arm 18 and the main part of the type bar 2, and the link 28 is slightly shorter than the link 17. Furthermore, the arc described by the arm 29 from dead center to printing position of the type bar 23 in the present instance approximates 10°, as compared to approximately 7° described by the arm 12 from dead center to printing position of the type bar 2. The arcs described by the arms 12 and 29, as well as the comparative lengths of the arms and links of these two embodiments may, of course, vary without departing from the general spirit of the invention.

In the embodiment illustrated in Figs. 3 and 4, in retracted position, the pin 30 at the free end of the link 31 will be positioned in the lobe 25 of the cam slot 24, in dead center position it will be positioned approximately at the conjunction of the lobes 25 and 26, and in printing position the pin 30 will be positioned in the lobe 26.

The fact remains, however, that the toggle action of the arm 29 and link 31 will cooperate with the control for the type bar 2 characterized by the link 28 and cam slot 24 in substantially the same way as the toggle action of the arm 12 and link 15 of the embodiment illustrated in Figs. 1 and 2 will cooperate with the control for the type bar 2 characterized by the links 17 and 16.

The embodiment illustrated in Figs. 5 and 6 is distinguished from the embodiment illustrated in Figs. 3 and 4 primarily in that the arm 28 of the embodiment illustrated in Figs. 3 and 4 is eliminated, and in place thereof the arm 32 is formed integral with the type bar 33, and the arm 32 or the type bar 33 in the area between the cam slot 34 and the enlargement 35 surrounding its fixed pivot pin 36, or both, is yieldable, being preferably composed of some flexible metal, so that when the arm 37 moves from the dead center position in Fig. 5 to the printing position of the type bar 33, this yieldability will permit the pin 38 of the link 39 to move from the conjunction between the lobes 40 and 41 of the cam slot 34 into the lobe 41.

It should also be noted that due to the fewer moving parts in the embodiments of Figs. 3 and 4 on the one hand, and Figs. 5 and 6 on the other hand, as compared to the embodiment illustrated in Figs. 1 and 2, the limiting stop, such as the limiting stop 21, may be dispensed with.

The embodiment illustrated in Figs. 7 and 8 is substantially identical to the embodiment illustrated in Figs. 1 and 2 except that the key bar 42 of this last embodiment is connected to the type bar 43 instead of being connected to the bell crank lever 44; see for comparison, the link 13 of the embodiment illustrated in Figs. 1 and 2.

In this last embodiment, the arm 45 of the type bar 43 is provided with an extension 46 beyond the pivotal connection of the arm 45 with the link 47, which extension 46 is in turn connected to the upper end of the arm 48 of the bell crank lever 49 by the link 50, the lower arm 51 of which bell crank lever 49 is connected to the key bar 42 by the link 52.

The embodiment illustrated in Figs. 7 and 8 is submitted primarily to illustrate the flexibility of

this typewriter action with respect to its connection to a key bar to fit in with various conventional typewriter constructions on the market today.

It is obvious that various changes and modifications may be made to the details of construction without departing from the general spirit of the invention as set forth in the appended claims.

I claim:

1. The combination with a platen, of a key bar pivotally mounted on a fixed pivot, a linkage including a type bar pivotally mounted on a fixed pivot and having a head thereon, said type bar having an extension beyond its fixed pivot, an arm pivotally mounted on a fixed pivot, a link pivotally connected at one end to one end of said arm, a control including a first means and a second means, said first means extending from said extension to said link and pivotally connected to said link intermediate its ends, said second means operatively associating the other end of said link with said type bar adjacent its head to vary the distance between said head and said other end of said link as the head is moved into and out of printing relation to said platen, a spring operatively connected to said linkage normally to maintain it and return it to position of rest, and means for operatively connecting said linkage to said key bar to actuate said linkage and therewith said type bar into printing relation with said platen when said key bar is actuated in opposition to said spring, said arm and link forming a toggle action and when actuated by said key bar performing an initial accelerated motion before reaching dead center and thereupon performing a decelerated motion characterized by a pressure thrust when passing dead center.

2. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a link pivotally connected at one end to one end of said lever, a control including a first means and a second means, said first means extending from said extension to said link and pivotally connected to said link intermediate its ends, said second means operatively associating the other end of said link with said type bar adjacent its head to vary the distance between said head and said other end of said link as the head is moved into and out of printing relation to said platen, and means for operatively connecting said linkage to said key bar to actuate said linkage and therewith said type bar into printing relation with said platen in opposition to said spring when said key bar is actuated, said lever and link forming a toggle action and when actuated by said key bar performing an initial accelerated motion before reaching dead center and thereupon performing a decelerated motion characterized by a pressure thrust when passing dead center.

3. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally

maintaining said linkage in position of rest and for restoring it to position of rest, a first link pivotally connected at one end to the end of the other arm of said lever, a control including a first means and a second means, said first means extending from said extension to said first link and pivotally connected to said first link intermediate its ends, said second means operatively associating the other end of said first link with said type bar adjacent its head, and a second link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

4. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including a first means and a second means, said first means comprising a second link pivotally connected at one end to one end of said extension and at its other end pivotally connected to said first link intermediate its ends, said second means operatively associating the other end of said first link with said type bar adjacent its head, and a third link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

5. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to one end of said lever, a control including a first means and a second means, said first means comprising a second link pivotally connected at one end to one end of said extension and at its other end pivotally connected to said first link intermediate its ends, said second means operatively associating the other end of said first link with said type bar adjacent its head, and means for operatively connecting said linkage to said key bar to actuate said linkage and therewith said type bar into printing relation with said platen in opposition to said spring when said key bar is actuated, said lever and first link forming a toggle action.

and when actuated by said key bar performing an initial accelerated motion before reaching dead center and thereupon performing a decelerated motion characterized by a pressure thrust when passing dead center.

5. The combination with a platen, of a key bar pivotally mounted on a fixed pivot, a first linkage including a type bar pivotally mounted on a fixed pivot and having a head thereon, said type bar having an extension beyond its fixed pivot, a lever fulcrumed on a fixed pivot, a spring connected to one arm of said lever for normally maintaining said first linkage in position of rest and for restoring it to position of rest, a first link pivotally connected at one end to one end of said lever, a control including a second link pivotally connected at one end to one end of said extension and at its other end pivotally connected to said first link intermediate its ends, said control also including a third link pivotally connected at one end to the other end of said first link and at its other end pivotally connected to said type bar adjacent its head, and means for operatively connecting said first linkage to said key bar to actuate said first linkage and therewith said type bar into printing relation with said platen in opposition to said spring when said key bar is actuated, said lever and first link forming a toggle action and when actuated by said key bar performing an initial accelerated motion before reaching dead center and thereupon performing a decelerated motion characterized by a pressure thrust when passing dead center.

35. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including a second link pivotally connected at one end to one end of said extension and at its other end pivotally connected to said first link intermediate its ends, said control also including a third link pivotally connected at one end to the other end of said first link and at its other end pivotally connected to said type bar adjacent its head, and a third link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

65. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including an auxiliary bar

integral with and extending from said extension to said first link and pivotally connected to said first link intermediate its ends, said control also including a cam slot in said type bar adjacent its head, a pin at the free end of said first link riding in said slot, and said type bar being yieldable in part to enable the head of said type bar to be deflected from said auxiliary bar when in printing relation to said platen, and a second link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

9. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including a second link pivotally connected at one end to one end of said extension and at its other end pivotally connected to said first link intermediate its ends, said control also including a cam slot in said type bar adjacent its head, and a pin at the free end of said first link riding in said slot, and a third link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

10. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to one end of said lever, a control including a first means and a second means, said first means comprising a second link pivotally connected at one end to one end of said extension and at its other end pivotally connected to said first link intermediate its ends, said second means operatively associating the other end of said first link with said type bar adjacent its head, means for operatively connecting said linkage to said key bar to actuate said linkage and therewith said type bar into printing relation with said platen in opposition to said spring when said key bar is actuated, said lever and first link forming a toggle action and when actuated by said key bar performing an initial accelerated motion before reaching dead center and thereupon performing a decelerated motion characterized by a pressure thrust when passing dead center.

5 pressure thrust when passing dead center, a first stop determining the position of said type bar in position of rest, and a second stop for arresting said lever when said type bar is in printing relation with said platen.

11. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a link pivotally connected at one end to one end of said lever, a control including a first means and a second means, said first means extending from said extension to said link and pivotally connected to said link intermediate its ends, said second means operatively associating the other end of said link with said type bar adjacent its head to vary the distance between said head and said other end of said link as the head is moved into and out of printing relation to said platen, means for operatively connecting said linkage to said key bar to actuate said linkage and therewith said type bar into printing relation with said platen in opposition to said spring when said key bar is actuated, said lever and link forming a toggle action and when actuated by said key bar performing an initial accelerated motion before reaching dead center and thereupon performing a decelerated motion characterized by a pressure thrust when passing dead center, and a stop for arresting said lever when said type bar is in printing relation with said platen.

12. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to one arm of said lever for normally maintaining said linkage in position of rest and for restoring it to position of rest, a first link pivotally connected at one end to the end of the other arm of said lever, a control including an auxiliary bar integral with and extending from said extension to said first link and pivotally connected to said first link intermediate its ends, said control also including a cam slot in said type bar adjacent its head, a pin at the free end of said first link riding in said slot, and said type bar being yieldable in part to enable the head of said type bar to be deflected from said auxiliary bar when in printing relation to said platen, a second link pivotally connected at one end to said key bar and at its other end pivotally connected to said one arm of said lever to actuate said first linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center, and a stop for arresting said lever when said type bar is in printing relation with said platen.

13. The combination with a platen, of a key bar pivotally mounted on a fixed pivot, a linkage including a type bar pivotally mounted on a fixed pivot and having a head thereon, said type bar having an extension beyond its fixed pivot, a lever fulcrumed on a fixed pivot, a spring connected to

one arm of said lever for normally maintaining said linkage in position of rest and for restoring it to position of rest, a first link pivotally connected at one end to the end of the other arm of said lever, a control including a second link pivotally connected at one end to one end of said extension and at its other end pivotally connected to said first link intermediate its ends, said control also including a cam slot in said type bar adjacent its head, and a pin at the free end of said first link riding in said slot, a third link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

14. The combination with a platen, of a key bar pivotally mounted on a fixed pivot, a linkage including a type bar pivotally mounted on a fixed pivot and having a head thereon, a lever fulcrumed on a fixed pivot, a spring connected to one arm of said lever for normally maintaining said linkage in position of rest and for restoring it to position of rest, a first link pivotally connected at one end to the end of the other arm of said lever, a control including an auxiliary bar integral with said type bar and extending from its fixed pivot to said first link and pivotally connected to said first link intermediate its ends, said control also including a cam slot in said type bar adjacent its head, a pin at the free end of said first link riding in said slot, and said auxiliary bar and type bar being yieldable in part to enable the head of said type bar to be deflected relative to said auxiliary bar when in printing relation to said platen, and a second link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

15. The combination with a platen, of a key bar pivotally mounted on a fixed pivot, a linkage including a type bar pivotally mounted on a fixed pivot and having a head thereon, a lever fulcrumed on a fixed pivot, a spring connected to one arm of said lever for normally maintaining said linkage in position of rest and for restoring it to position of rest, a first link pivotally connected at one end to the end of the other arm of said lever, a control including an auxiliary bar integral with said type bar and extending from its fixed pivot to said first link and pivotally connected to said first link intermediate its ends, said control also including a cam slot in said type bar adjacent its head, a pin at the free end of said first link riding in said slot, and said auxiliary bar being yieldable to enable the head of said type bar to be deflected relative to said auxiliary bar

when in printing relation to said platen, and a second link pivotally connected at one end to said key bar and at its other end pivotally connected to said one arm of said lever to actuate said linkage and therewith said type bar into printing relation with said platen when said key bar is actuated in opposition to said spring, said lever and first link forming a toggle action and when actuated by said key bar performing an initial accelerated motion before reaching dead center and thereupon performing a decelerated motion characterized by a pressure thrust when passing dead center.

16. The combination with a platen, of a key bar pivotally mounted on a fixed pivot, a linkage including a type bar pivotally mounted on a fixed pivot and having a head thereon, an arm pivotally mounted on a fixed pivot, a link pivotally connected at one end to one end of said arm, a control including a first means and a second means, said first means extending from said type bar to said link and pivotally connected to said link intermediate its ends, said second means operatively associating the other end of said link with said type bar adjacent its head to vary the distance between said head and said other end of said link as the head is moved into and out of printing relation to said platen, a spring operatively connected to said linkage normally to maintain it and return it to position of rest, and means for operatively connecting said linkage to said key bar to actuate said linkage and therewith said type bar into printing relation with said platen when said key bar is actuated in opposition to said spring, said arm and link forming a toggle action and when actuated by said key bar performing an initial accelerated motion before reaching dead center and thereupon performing a decelerated motion characterized by a pressure thrust when passing dead center.

17. The combination with a platen, of a key bar pivotally mounted on a fixed pivot, a linkage including a type bar pivotally mounted on a fixed pivot and having a head thereon, two interconnected toggles having an intermediate common member, one end of said interconnected toggles pivotally connected to said type bar, a control means pivotally connected at one of its ends to said intermediate common member intermediate its ends and at its other end pivotally connected to said type bar, the other end of said interconnected toggles pivotally mounted on a fixed pivot, a spring operatively connected to said linkage normally to maintain it and return it to position of rest, and means for operatively connecting said linkage to said key bar to actuate said linkage and therewith said type bar into printing relation with said platen when said key bar is actuated in opposition to said spring, said interconnected toggles when actuated by said key bar performing an initial accelerated motion before reaching dead center and thereupon performing a decelerated motion characterized by a pressure thrust after passing dead center.
